UNITED STATES PATENT OFFICE.

CHARLES S. SINCLAIR, OF CINCINNATI, OHIO, ASSIGNOR TO THE R. F. JOHNSTON PAINT COMPANY, OF CINCINNATI, OHIO, A CORPORATION OF OHIO.

REDECORATION PROCESS.

Application filed July 9, 1923. Serial No. 650,220.

To all whom it may concern:

Be it known that I, CHARLES S. SINCLAIR, a citizen of the United States of America, and a resident of Cincinnati, in the county of Hamilton and State of Ohio, have invented a new and useful Improvement in a Redecoration Process, of which the following is a specification.

An object of my invention is to provide a process for renovating or redecorating floor coverings and the like, of which linoleum and oil cloth are examples.

Another object of my invention is to provide a simple efficacious and expedient process for the purpose stated.

These and other objects are attained by the means described herein and disclosed in the accompanying drawings, in which:

Fig. 1 represents a plan view of a fragment of oil cloth or linoleum showing various steps of my process.

Fig. 2 is a sectional view on line 2—2 of Fig. 1.

Fig. 3 is a sectional view on line 3—3 of Fig. 1.

After linoleums and oil cloths, other than inlaid linoleums, have been in use for some time, the design or surface ornamentation thereof depicted at 4, becomes worn and eradicated at places, wherefore the linoleum presents an unsightly appearance and requires much effort with but little noticeable effect upon the part of the housewife for keeping same in a clean and inoffensive appearing condition. My invention is con-

cerned in resurfacing linoleum and the like when they reach such a condition. In carrying out my invention the linoleum as shown at 4, is resurfaced or recovered with a ground color or coloring 5 that may be of any suitable color. This resurfacing is preferably of paint. After the ground color 5 has been applied, a suitable design 6 may be worked upon or over the ground color. This design may be applied in any suitable manner such as by stippling. The stippling may be accomplished in any number of colors, and by any suitable means such as by employing a sponge that is dipped in the color and then placed lightly upon the surface of the ground 5. The material used for so stippling the linoleum may be water color or an oil paint. Water color has been found to give very good results. After the coloring applied by the stippling process 55 has dried, a coat of varnish 7 is applied over the treated surface. After the varnish has dried the linoleum may be washed up as is common practice with linoleums not so treated.

What I claim is:

The process of renovating linoleum and the like comprising applying a ground covering to the wearing surface of the linoleum, stippling over the ground color, and varnishing over the ground color and stippling.

In testimony whereof, I have hereunto subscribed my name this 5th day of July, 1923.

CHARLES S. SINCLAIR.
